CLAIM

The ornamental design for the louvered door cleaner, as shown and described.

DESCRIPTION

FIG. 1 is an exploded front elevational view of the louvered door cleaner shown in FIG. 7;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view of a louvered door cleaner showing my new design.

The broken criss-crossed lines of FIGS. 1, 2, 4, 5, and 6 represent a textured surface.
